UNITED STATES PATENT OFFICE.

JAMES M. WORKMAN AND FREDERICK W. GRAHAM, OF GREENVILLE, SOUTH CAROLINA.

WINDOW-SASH OPENER.

1,356,802.

Specification of Letters Patent. Patented Oct. 26, 1920.

Application filed April 9, 1917. Serial No. 160,646.

To all whom it may concern:

Be it known that we, JAMES M. WORKMAN and FREDERICK W. GRAHAM, citizens of the United States, and residents of Greenville, 5 county of Greenville, and State of South Carolina, have invented an Improvement in Window-Sash Openers, of which the following is a specification.

The object of our invention is to provide 10 an effective means for operating pivoted or hinged window sashes, more especially for factory buildings and large public halls or auditoriums, the construction being so designed as to enable the sash to be positioned 15 to various degrees of opening and held in such positions, but at all times capable by easy manipulation by an attendant, to change the angles of or close the sash.

In general, our invention comprehends a 20 pivoted window sash to which is hinged an operating bar associated with operating chains or cables by which the window sash may be tilted from a closed position to any angle of opening, the said operating mechanism being provided with means for holding the sash in position when opened to the desired degree, all of which is more fully described hereinafter and specially pointed out in the claim.

Our improvements will be better understood by reference to the accompanying drawings, in which: Figure 1 is a vertical section of a portion of a window frame and pivoted sash showing our improvements applied thereto when the sash is held in open position; Fig. 2 is a similar view but with the operative parts manipulated to permit the sash to be closed; Fig. 3 is a vertical sectional view illustrating the window sash in closed position; Fig. 4 is a vertical section corresponding to Fig. 3 but showing a modification of our invention; Fig. 5 is an elevation of the specially constructed sheave shown in Fig. 4; and Fig. 6 is a front view 45 of the bracket and attached parts in Fig. 1.

2 is the fixed member of the window sash and 3 indicates the usual hinged or pivoted sash member thereof which in many cases is of considerable size, constituting approximately one-half of the whole window. 4 is an operating bar which is hinged to the pivoted sash 3 at 5 and the said hinged end of the bar 4 is laterally curved as at 6, as indicated in Fig. 3, to enable it to bridge over 55 the operative mechanism when the window

sash 3 is closed. This bar 4 is provided with a plurality of lugs or teeth 7, spaced at intervals along its length and also has its lower or free end turned at an angle as indicated at 8 for connection with the end of 60 the operating chain or cable 18, employed in opening or controlling the closing of the sash. An operating chain or cable 17, for closing the sash, is connected to the bar 4 adjacent to its hinge point 5 with the sash 65 3, so that when a pull upon the chain or cable 17 is given, the power is applied to the sash 3 so close to the hinge 5 of the bar 4 that the pull in effect is substantially upon the sash. The chains or cables 17 and 18 70 pass about suitable guide pulleys 16 and depend to within easy reach of an operator and desirably connect in to a loop, as at 19. It will be understood that if the parts are in the relation illustrated in Fig. 3, a pull upon 75 the cable 18 would tend to raise the bar 4 and exert a lateral thrust at the hinge point 5, which would open the sash, allowing it to assume a position as indicated in Figs. 1 and 2. Means for retaining the bar 4 in the 80 position assumed are provided and comprise a cross bar 10 which is soldered at 11 with fusible solder to bracket 9 in which the grooved pulleys 16 are journaled. The lugs or teeth 7 of the bar 4 are inclined at the 85 forward ends so as to slide over this cross bar 10 and engage it in such a manner as to lock the bar against a return movement. To provide for the disengagement of the bar 4 with the cross bar 10, we employ a lever 12 90 which is hinged at 13 to the bracket 9, said lever having a short arm 14 projecting horizontally above the grooved wheels 16 and under the bar 4, and further having a downwardly extending arm carrying a grooved 95 pulley 15 over which the downwardly extending portion of the chain 17 passes. It will now be understood, that if the lower part of the chain 17 be pulled, the lever 12 will be oscillated, as clearly indicated in Fig. 100 2; and the result of this is, that the arm 14 forces the bar 4 upward within the guard 9a of the bracket, so that the lugs 7 thereof clear cross bar 10, and thereafter the manipulations of the two chains or cables 17 105 and 18 permit the bar 4 to move backward to close the sash 3 to any degree desired. By manipulating the chains or cables 17 and 18, the sash 3 may be moved toward and into a closed position upon the fixed sash 2. In 110

opening the window sash there will be no necessity of any pull upon the chain or cable 17, as the pull upon the cable 18 moves the bar 4 freely over the cross bar 10 to the position desired.

When the sash is fully closed (Fig. 3), and the bar 4 hangs in a vertical position, any attempt to open the sash 3 by directly pulling upon the same would be resisted 10 with an enormous leverage produced by the bar 4 which is of effectual lock against any wind pressures upon the sash, but the operating bar also has a lug 20 which engages the cross bar 10 in Fig. 3 and 21 in Fig. 5 15 to positively lock the sash against unlawful opening from the outside.

In case of fire, it is desirable that the window sash 3 should automatically close and this action is provided by having the cross 20 bar 10 connected in place upon the bracket 9 by fusible solder which fuses under the increased temperature and upon dropping away; permits bar 4 to move backward and downward and the window sash 3 to move 25 to a closed position by gravity. This cross bar 10 may be of any desired shape and the solder joint of any degree of strength to suit the requirements in any particular window construction.

30 In the modification shown in Fig. 4, the bracket 9 is provided with a specially constructed grooved sheave 16^a which has two main grooved portions 16^b and 16^c, the former of which is provided with a lateral grooved portion 16^e which continues in a further circumferential groove 16^d. The grooves 16^c and 16^d are relatively shallower than the grooves 16^b and 16^e and operate to provide a cam action upon the chain or cable 18 by jamming it against the wall 19 of the bracket 9 whenever it is desired to lock the bar 4^a from a return movement. The chain 17 for closing the sash is guided in the groove 16^c of the sheave 16^a whereas the cable 18 for lifting the bar 4^a and opening the sash 3 is guided in the groove 16^b of the sheave. The end 10^a of the bracket may be shaped to prevent disengagement of the chains or cables from the sheave. In manipulating the chain 18 to open the sash 3 and hold the bar 4^a to maintain the open position of the sash, the following operation is required: The chain 18 is pulled downward and when the sash 3 is opened to the desired 45 distance, the said chain is pulled laterally over the sheave so that it enters the groove 16^e and into the cam groove 16^d, then upon slightly relieving the pull upon the chain it will be carried upward and jammed between 50 the abutment 19 and the shallow grooved portion 16^d of the sheave, thereby retaining the bar 4^a and the sash in their open positions. To close the sash the chain 18 is pulled until it runs back into the groove 16^b,

and thereafter it is paid upward and if 65 desired, assisted by a downward pull upon the chain 17 until the parts arrive at the positions indicated in Fig. 4. As shown in this figure, there is a lug 20 upon the curved portion 6 of the bar 4^a, said lug being in 70 horizontal alinement with lug 21 on the bracket 9. The result of this is, that should an attempt be made to pull the window sash outward, the lug 20 will engage the lug 21, which will thereby act as a lock to prevent such opening. It is manifest that lugs 75 of this character 20 and 21 may be employed on the constructions of Fig. 3 equally well, if so desired.

While we have described the transverse bar 10 as being secured in place by fusible solder, it is to be understood that we do not restrict ourselves in that respect, as said bar may be firmly secured to or made integral with the bracket 9.

It will now be apparent that we have devised a novel and useful construction which embodies the features of advantage enumerated as desirable, and while we have in the present instance shown and described the preferred embodiment thereof which has been found in practice to give satisfactory and reliable results, it is to be understood that we do not restrict ourselves to the details, as the same are susceptible of modification 95 in various particulars without departing from the spirit or scope of the invention.

Having now described our invention, what we claim as new and desire to secure by Letters Patent, is:—

The combination of a fixed window frame, with a movable window sash therein, and means for operating the movable sash consisting of an operating bar hinged to the movable sash and provided with teeth, a bracket secured to the fixed window frame and having a detachable cross bar with which the teeth engage to hold the movable sash in open position, said bar secured in place wholly by fusible solder, a guide sheave on the bracket 105 a chain or cable guided about the sheave and having one end connected with the free end of the operating bar to open the sash and having the other end extending downward from the sheave and connected to operate the movable window sash and independently operable hand manipulated means for raising the operating bar out of engagement with the cross bar and to permit the closing 115 of the sash by gravity.

In testimony of which invention, we hereunto set our hands.

JAMES M. WORKMAN.
FREDERICK W. GRAHAM.
